BY Straker G. ATTY'S.

UNITED STATES PATENT OFFICE.

ROBERT H. WARREN AND DAVID WALKER, OF NEWARK, NEW JERSEY.

DESIGN FOR A STAIR-CARPET BUTTON.

SPECIFICATION forming part of Design No. 25,266, dated March 24, 1896.

Application filed February 27, 1896. Serial No. 581,070. Term of patent 7 years.

To all whom it may concern:

Be it known that we, ROBERT H. WARREN and DAVID WALKER, citizens of the United States, residing at Newark, in the county of 5 Essex and State of New Jersey, have invented and produced a new and original Design for Stair-Carpet Buttons; and we do hereby declare the following to be a full, clear, and exact description of the invention, such as will enable others skilled in the art to which it 10 pertains to make and use the same, reference being had to the accompanying drawings, and to letters of reference marked thereon, which form a part of this specification.

15 In the drawings, Figure 1 is an elevation, and Fig. 2 a central transverse section, of our newly-designed stair-carpet button, these views being deemed sufficient to fully illustrate our design.

20 The leading feature of our design consists in a stair-button angular in outline, and around the central perforation displaying a series of ornaments, and outside of and around these in turn displaying linear ornaments extending across the face of the button opposite the angles of the same, and together forming 25 an angular ornament, and outside of these in the angles of the button displaying other ornamental figures.

In said drawings, *a* indicates the button, 30 which is shown angular in outline centrally perforated, as at *b*, and centrally raised, as indicated in Fig. 2. Around the central perforation are displayed raised annular ornaments *c*, around which in turn is a series of radial oval ornaments *d d d* of varying lengths. Outside of and around these in turn are 35 curved linear ornaments *e e e* extending from side to side of the button and lying opposite the angles thereof, said linear ornaments together forming an angular ornament whose angles lie at the centers of the sides of the button. In the fields outlined by the sides of the button and the ornamental lines *e e e* are radial ornaments *f* faced with roundels *g*. 40 45

What we claim is—

The design for a stair-carpet button herein shown and described.

In testimony that we claim the foregoing we have hereunto set our hands this 6th day of 50 February, 1896.

ROBERT H. WARREN.
DAVID WALKER.
